MOVING PICTURE REEL

Application filed October 20, 1930. Serial No. 489,844.

This invention relates to improvements in moving picture reels.

It is the object of this invention to produce a moving picture reel of great strength and rigidity, which is made of two parts and secured together with means that holds the parts in adjusted position and which prevents relative rotation of the parts when they are assembled.

The above and other objects that may become apparent as this description proceeds are attained by means of a construction and an arrangement of parts that will now be described in detail, and for this purpose reference will be had to the accompanying drawings in which the invention has been illustrated, and in which:

Fig. 1 is a side elevation of the improved reel;

Fig. 2 is a view showing the reel as it appears from a point lying in its plane of rotation;

Fig. 3 is a view taken on line 3—3, Fig. 2, and shows the inner surface of the center portion of one of the reel members;

Fig. 4 is a section taken on line 4—4, Fig. 3, and shows the means for connecting the two parts of the reel, and

Fig. 5 is a plan view of the spacing member employed in the assembly of the reel.

In the drawings reference numerals 1 indicate the two parts of the reel assembly, which parts are identical, each consisting of a circular rim 2 and a circular central portion 3 connected by radial spokes 4. The central portion is provided with a circular depression 5 that is concentric with rim 2. Each of the parts 1 are also provided with a circular flange 6 that extends inwardly in the direction of the depression 5 and which are adapted to fit one against the other in the manner shown in Figs. 2 and 4. The depth of the depression 5 is such that the bottom walls thereof, which have been indicated by reference numeral 7, do not come in con-

tact but are separated by a space in the manner shown in Fig. 4. The circular walls 7 have each a central opening 8 and are provided on their inner surfaces with recesses 9, and are also provided with an opening 10 corresponding to each of the recesses. In the drawing the recesses have been shown as formed by projecting flanges 11 that extend beyond the surface of walls 7, but they may be formed by making depressions in the surface or in any other suitable way.

For the purpose of holding the two parts of the reel in assembled position, a spacer has been provided. This spacer has been shown in plan view in Fig. 5, and has been designated in its entirety by reference numeral 12. The specific embodiment of the spacer, illustrated in the drawing, comprises a triangular member 13 having a central hub 14 extending from each of its opposite sides. At each corner of the triangular part 13 and on each side thereof is a circular projection 15 that is adapted to fit into a recess 9 in the manner shown in Fig. 4. At each corner of member 13 an opening 16 is provided, which openings register with openings 10 so as to form passageways for the clamping bolts 17 that extend through the two reel members and through the spacer in the manner shown in Fig. 4. The parts are so proportioned that when the bolts 17 are tightened the edges of flanges 6 will be forced into contact with each other, after which the central portions of the members will yield slightly so as to come into contact with the ends of the circular projections 15. Since the circular projections 15 are designed to fit snugly into the recesses 9, they resist any force tending to rotate members 1 relative to each other and thereby remove any such strains from the clamping bolts.

Another function of projections 15 and recesses 9 is to properly center the parts so that the outer surfaces of flanges 6 will automatically be brought into the same cylindrical surface.

In the illustration shown on the drawings and described above the interconnecting means for preventing relative rotation between the two members of the reel has been shown as comprising the recesses 9 and the lugs 15, but it is to be understood that other equivalent means may be substituted for the lugs and recesses and that this construction is merely illustrative of means for this purpose and is not to be construed as limiting the invention to this specific means to any greater extent than necessary by the state of the prior art.

Reels made in accordance with the invention above described are usually cast from aluminum and the outer surfaces of flanges 16 are machined to make them true cylinders and of exactly the same diameter. Flanges 6 are also provided with cuts 18 that serve as means for attaching the end of the film to the reel and which also prevents strains due to temperature changes.

Having described the invention what is claimed as new is:

1. A motion picture reel consisting of two similarly shaped members each having a circular rim and a circular center portion connected by a plurality of radial spokes, the center portion of each member having a circular flange of uniform width adapted to coact with the flange of the other member to form a cylindrical surface extending between the two members and which forms the central surface of the spool, and means for interconnecting the members, said means comprising a spacer provided with holes for the reception of clamping bolts, the two spaced members having corresponding holes for the reception of the bolts, the surfaces of the spacer and the surfaces of the two members having interlocking means to positively position the several parts and to hold them against relative rotary motion.

2. In a moving picture reel composed of two substantially identical, circular members each of which has a circular rim and a central circular portion connected by means of spokes, one side of the central portion of each having a circular flange of uniform width that is adapted to cooperate with the corresponding flange on the other to form a cylindrical surface, the central portion of each member having its center offset into the space bounded by the circular flange, means for holding the two members in assembled position and for interlocking them against relative rotation, said means comprising a spacer located between the adjacent surfaces of the members, the spacer and the members being provided with openings for the reception of clamping bolts and with interengaging latching means for holding the parts in predetermined position.

3. A moving picture reel comprising two substantially identical parts each having a

circular rim and a central portion provided on one side with a circular flange of uniform width, a spacer located between the two parts within the space enclosed by the flanges, the spacer and the two parts of the reel having 70 registering openings for the reception of clamping bolts and means for interlocking the spacer and the two reel parts for holding them in a predetermined relative rotary position independently of the clamping bolts 75 and the flanges.

In testimony whereof we affix our signatures.
